UNITED STATES PATENT OFFICE.

JOHN ROGGINER, OF CHICAGO, ILLINOIS.

EXTENSION TABLE.

1,414,304.

Specification of Letters Patent. Patented Apr. 25, 1922.

Application filed February 11, 1920. Serial No. 357,930.

To all whom it may concern:

Be it known that I, JOHN ROGGINER, citizen of the United States, residing at Chicago, in the county of Cook and State of Illinois, have invented certain new and useful Improvements in Extension Tables; and I do hereby declare the following to be a full, clear, and exact description of the invention, such as will enable others skilled in the art to which it appertains to make and use the same.

My invention relates to tables and has special reference to improvements in extension top tables.

15 The object of my invention is to provide a table, having a fixed pedestal, with a top adapted to be adjusted to different dimensions and a simple, strong and easily operable locking device for holding the top 20 firmly locked in its adjusted position.

My invention consists in an extension top table, provided with a unique locking device which is capable of locking the parts of the top together in the several positions thereof.

25 My invention also consists in a locking device for extension top tables comprising means for operatively joining the two main parts of the top for equal out and in movement, and a yielding lever mechanism for 30 forcibly drawing the two parts toward each other and holding them against separation.

My invention also consists in the several features of construction and in the combinations and arrangements of parts and devices 35 by means of which I am enabled to attain the above-mentioned and other objects, and all as hereinafter described and particularly pointed out in the appended claims.

My invention will be more readily understood by reference to the accompanying drawings forming part of this specification and in which—

40 Fig. 1 is a top plan view of a table embodying my invention, the table top being shown in dotted lines only, and in closed position;

45 Fig. 2 is a fragmentary top plan view of the table shown in partly extended position in full lines and in its fully extended position in dotted lines;

50 Fig. 3 is a central vertical longitudinal section on the line 3—3 of Fig. 2;

55 Fig. 4 is a partial sectional view through the right hand portion of Fig. 2, taken on a horizontal line slightly above the sectional

line 3—3 and looking in the opposite direction.

Fig. 5 is a horizontal section on the line 5—5 of Fig. 4;

60 Figs. 6 and 7 are detail vertical sections on the lines 6—6 and 7—7 respectively of Fig. 4.

In said drawings I have shown a fixed or rigid pedestal 1, forming the support for the table and having a flat upper end 2 65 upon which the guide rails 3 are fixed. The table top consists of two end members 4 and 5 which are mounted to slide back and forth on the guide rails 3 by means of longitudinal parallel guides 6 fixed to the underside of said top members. The guide rails not only serve to guide the parts of the top in their back and forth movement, but, as usual, also serve to hold the two parts in the same plane, and to support the additional table boards, which are commonly used to fill in between the two end members when the top is extended.

70 When the two parts 4 and 5 of the table top are placed to form a top of the shortest length, their inner edges contact on a transverse center line as shown in Fig. 1, and from this position they can be separated to the largest dimension of top as shown in dotted lines in Fig. 2.

85 For the purpose of causing the two parts of the top to move out and in the same distance so that the table top will always be central over the pedestal I provide a horizontal swinging arm or lever 7 pivotally mounted at its center on a vertical pivot 8 at the center of the pedestal to swing over the pedestal. I connect the outer ends of this swinging lever to the underside of the two end members 4 and 5 of the top by links 9 and 10 respectively, which are pivotally secured to respective members at their respective ends so that as one member of the table top is moved out or in the other member moves likewise and in unison therewith. To limit the outward movement of the two members of the top I provide a stop 11 fixed upon the upper end of the pedestal in the path of one end of the swinging lever 7.

100 By taking hold of one of the table top parts it and the opposite member can be readily moved out or in to adjust the top to any desired length. If the desired length is the smallest dimension, the two parts 4 110

and 5 are brought together until their inner edges contact above the center of the pedestal, and if it is desired to make the table top longer than the minimum length, the two parts 4 and 5 are separated sufficiently to admit one or more extra or intermediate table boards between the inner edges of the two parts 4 and 5 and then the two parts 4 and 5 are pushed toward each other to contact 10 with these extra leaves.

For the purpose of locking the end parts 4 and 5 against separation either in contact with each other or against any intermediate table boards which may be used, I provide 15 a yielding table lock which is adapted to hold the parts constantly pressed together or toward each other with a yielding pressure and which, being once set, remains in such position until again released.

20 Said lock comprises a longitudinally arranged and relatively movable rack-like member 12 mounted upon the lower side of one of the table top members as 5, the teeth 13 thereof projecting downwardly, and a 25 stop member 14 mounted upon the upper end of the pedestal adapted to be engaged by said teeth.

The rack 12 is slightly longer than the total movement of the member 5, by which 30 it is carried, and it is so related to the stop member 14 that said member 14 can always be engaged by one of the teeth of the rack regardless of the relative position of the member 5 and the pedestal.

35 When the rack is engaged with the stop 14 the table top members are not free to move, but may be moved a slight distance by the engaging mechanism to tightly close the top and hold the several parts against separation.

40 To engage and disengage the rack and stop I mount the rack so that it has a slight vertical movement. In its upper position, as shown in dotted lines in Fig. 4, the teeth 45 are free of the stop and the rack with the table top parts can be freely moved back and forth, and when the rack is in its lower position, as shown in full lines, the stop is engaged by the rack and the rack is held 50 against movement.

For mounting the rack for movement as described, I secure a longitudinal guide bar 15 to the lower face of the member 5, having horizontally extending flanges 16 for securing it in place by screws 18, and a depending flange 17 against which the rack is positioned. I provide offset or cam-guide slots 19 in the guide bar 15 spaced longitudinally therein and adapted to receive rigid guide 55 pins or lugs 20 carried by the rack bar. The rack is held against removal by washers 21 and heads 22 formed on the guide pins.

The two guide slots 19 are exactly similar, and each has an elongated lower horizontal part 19', a shorter horizontal part 19"

and an inclined part 19'' joining the upper and lower parts. The pins 20 are spaced equally with the spacing of the two guide slots and consequently as the rack bar is moved back and forth relatively to the guide bar the pins, by reason of their movement in said guide slots, cause the rack to be maintained in parallel relation to the table top and to be moved up and down to the extent of the vertical distance between the upper 75 and lower parts of said guide slots.

For the purpose of conveniently controlling the movement of said rack bar, I provide a hand lever or latch 23 pivotally mounted at one end to swing longitudinally relatively to the rack bar, on the rear or outer end of said guide bar 15 by a pivot 24. The lever 23 is adapted to swing back and forth beneath the table top, and to be limited in one direction by striking the underside of said top. Between the ends of the lever I secure one end of a tension spring 25 by a rivet 26, and I secure the other end of the spring to the rear end of the rack bar 12 by a rivet 27 and consequently, by swinging the lever back and up against the table top the rack is pulled back or outward in accordance with the strength of the spring 23. I prefer to use a coiled spring and I form it so that when the spring is not under tension the coils thereof are in close contact, in which condition the spring serves as a link to push the guide bar 15 forward when the lever 23 is swung forward. As the lever 23 is swung back and forth the rack bar is not only moved relatively back and forth, but by reason of the cam guide slots 19 it is also raised and lowered as described. The first action of the lever 23 in moving the rack from its upper position is to draw it down 100 by reason of the inclined portions of the cam slots for engagement with the stop 14, and then as the lever 23 is swung farther the rack is drawn backward or, in other words, the table top is forced inward, the stop 14 at such time holding the rack against movement. The first action of the lever 23 in moving the rack from its upper position is to draw it down 105 by reason of the inclined portions of the cam slots for engagement with the stop 14, and then as the lever 23 is swung farther the rack is drawn backward or, in other words, the table top is forced inward, the stop 14 at such time holding the rack against movement. The first action of the lever 23 in moving the rack from its upper position is to draw it down 110 by reason of the inclined portions of the cam slots for engagement with the stop 14, and then as the lever 23 is swung farther the rack is drawn backward or, in other words, the table top is forced inward, the stop 14 at such time holding the rack against movement. The first action of the lever 23 in moving the rack from its upper position is to draw it down 115 by reason of the inclined portions of the cam slots for engagement with the stop 14, and then as the lever 23 is swung farther the rack is drawn backward or, in other words, the table top is forced inward, the stop 14 at such time holding the rack against movement. The first action of the lever 23 in moving the rack from its upper position is to draw it down 120 by reason of the inclined portions of the cam slots for engagement with the stop 14, and then as the lever 23 is swung farther the rack is drawn backward or, in other words, the table top is forced inward, the stop 14 at such time holding the rack against movement. The first action of the lever 23 in moving the rack from its upper position is to draw it down 125 by reason of the inclined portions of the cam slots for engagement with the stop 14, and then as the lever 23 is swung farther the rack is drawn backward or, in other words, the table top is forced inward, the stop 14 at such time holding the rack against movement. The first action of the lever 23 in moving the rack from its upper position is to draw it down 130 by reason of the inclined portions of the cam slots for engagement with the stop 14, and then as the lever 23 is swung farther the rack is drawn backward or, in other words, the table top is forced inward, the stop 14 at such time holding the rack against movement.

I preferably make the stop member 14 somewhat yielding, in a downward direction, so that the rack can be entered into proper engagement therewith even though the lower end of a tooth might strike the upper edge of the stop as the rack is being lowered.

For this purpose I make the stop 14 of spring wire in the form of a rearwardly inclined loop having a cross-bar 28 at its upper or free end and secured at its lower end 5 to the top of the pedestal. The rack is adapted to engage the cross-bar 28 and in order to protect the stop against too great a strain which might occur through an attempt to move the table top without lifting the rack, 10 and for the purpose of holding the cross-bar at a definite height ready to receive the rack, I provide a relatively rigid stop 29 having two parallel rearwardly inclined hook-like tongues 30 fitting within the stop 14 and inclined over the cross-bar 28. The tongues 30 are separated laterally to provide a free space to receive the rack and to permit it to engage the cross-bar 28, as shown in Fig. 7.

The stop 14 is normally held by its own resilience against the underside of the fixed stop in position to be depressed, if a tooth of the rack should contact with it as the rack is being lowered. Should this occur the further movement of the lever 23, as explained, would draw the rack back and the stop 14 would then spring up into the next adjacent slot or space in the rack and engage the next adjacent tooth. I provide sufficient horizontal movement to the rack, once it is depressed, to insure the proper locking of the top even though the rack should first depress the stop 14, and furthermore, I provide sufficient horizontal movement to the rear connection of the spring 25 to the lever 35 23 to hold the parts of the table top together with enough pressure so that they cannot be inadvertently separated in moving the table about.

The main parts of the table and the several 40 extra boards are provided with the usual dowels 31 and sockets 32 to hold the parts in proper alignment. The several parts being locked in the positions shown in Fig. 1 and it being desired to enlarge the table top, the 45 lever 23 is first depressed to raise the rack and free the same from the stop 14, the two ends 4 and 5 are then separated to admit the necessary table boards between them, then the two ends are closed upon the boards 50 bringing all the parts substantially into contact, and the lever 23 is then raised, depressing the rack and engaging it with the stop 14; a further movement of the lever, serves to press the several parts of the top together 55 with the pressure due to the tension of the spring 25, and the final movement locks the lever 23 in its locking position, as described.

I claim as my invention:

1. In an extension table having two opposed table top members mounted on a pedestal and linked together for equal out and in movement, a stop on said pedestal, a relatively longitudinally movable bar on one of said members having a series of 65 teeth adapted for engagement with said stop,

a lever carried by said member and yielding means connecting said lever with said bar for moving the bar to engage said stop and for forcing said members toward each other.

2. In mechanism for locking the parts of an extension table top having two members linked together for equal out and in movement, a yielding projection adapted to be mounted and held stationary relatively to 70 said table top, a longitudinally arranged rack bar carried by one of said members adapted for engagement with said projection, means carried by said member for moving said rack bar vertically for engaging and disengaging said projection and for moving said rack bar longitudinally to force said table top members toward each other.

3. In mechanism for locking the parts of an extension table top having two members 85 linked together for equal out and in movement, a yielding projection fixed relatively to said members, a longitudinally arranged bar carried by one of said members having teeth for engagement with said projection, 90 said bar also having guide pins, a guide fixed on said member provided with forward and rear cam guide slots receiving said guide pins and adapted, as said bar is moved back and forth, to hold said bar horizontally and 95 lower and raise the bar for engaging and disengaging said projection, a hand lever pivotally mounted on said guide and a yielding link connected at one end to said lever between its ends and at its other end to the 100 rear end of said bar and adapted to yieldingly pull said bar rearwardly for forcing said table top members toward each other, the connection of said link with said lever being adapted to pass centers with the pivot 105 upon which said lever is mounted for locking said lever at one limit of its movement.

4. Mechanism for locking the opposed members of an extension table top which are connected for simultaneous out and in movement and comprising a projection fixed in relation to said members, a longitudinally arranged bar carried by one of said members adapted to be engaged with said projection in any relative position of the member by 110 which it is carried, means for disengaging said bar and projection to permit the free out and in movement of said members and means engaging said bar with said projection and for moving the bar longitudinally 115 relatively to the member carrying it for forcing said members toward each other, and means for yieldingly locking said bar relatively to said member for holding said members against separation.

5. In mechanism for locking the relatively movable members of an extension table top having two opposed members linked together for simultaneous out and in movement, a rack bar carried by one of said 120 125 130

members, a projection fixed in relation to said members adapted to be engaged by said rack bar in any relative position of the member carrying same, a guide by which the bar is carried, cam slots in the guide, pins carried by the bar and engaging within the slots for causing the bar to be raised and lowered adjacent to one limit of its movement for engaging and disengaging said projection, means for moving the bar back and forth, said projection being resilient and adapted to yield in a direction away from said bar to permit said up and down movement thereof and the engagement thereof 10 with said projection.

6. In mechanism for locking the parts of an extension table top having two opposed movable members, means for holding one of said members against movement away from the other, and means for forcing said other member toward the held member, comprising a stop fixed relatively to said members, a longitudinally arranged rack bar carried by said other member for engaging said stop, and means for yieldingly moving said rack bar relatively to the member carrying same for yieldingly forcing said member toward the opposite member.

JOHN ROGGINER.
